UNITED STATES PATENT OFFICE.

ALVAH BUSHNELL, JR., OF PHILADELPHIA, PENNSYLVANIA.

CARD-HOLDER FOR ENVELOPS AND WALLETS.

1,345,993.

Specification of Letters Patent.

Patented July 6, 1920.

Application filed January 6, 1919. Serial No. 269,776.

To all whom it may concern:

Be it known that I, ALVAH BUSHNELL, Jr., a citizen of the United States, residing at Philadelphia, in the county of Philadelphia and State of Pennsylvania, have invented 5 new and useful Improvements in Card-Holders for Envelops and Wallets, of which the following as a specification.

My invention relates to new and useful 10 improvements in card holders for envelops and wallets and the like and more particularly to card holders for devices of this character which are to be used for holding papers of different kinds to be held for reference, filed away or placed in a file or cabinet.

A further object of the invention is to provide a card holder for envelops, wallets, filing folders or other devices of this 20 character wherein there will be no transverse obstructions on the faces of such devices thereby permitting the easy insertion or withdrawal between or from a number of similar devices.

25 A further object of the invention is to so construct a card holder for envelops or wallets that the card held therein will be free or uncovered along two edges to permit the use of the card for printing matter, the entire length thereof or from one free edge to another.

A still further object of the invention is to provide a card holder for envelops or wallets comprising two strips or runners carried by the outer wall of the envelop or wallet either by forming said runners of separate pieces or constructing them as an integral part of the outer wall, said outer wall being produced either with or without a 35 flap and when formed in the latter way the envelop or wallet may be, if found desirable, provided with a flap, the same being produced from the inner wall of the wallet.

Another object of the invention is to form 45 the runners of single thickness throughout a portion of their width and of double thickness throughout the other portion by folding one part of the runner upon itself so that the fold or crease becomes the free edge beneath which the card is to be inserted.

With these ends in view, this invention consists in the details of construction and

combination of elements hereinafter set forth and then specifically designated by the claims.

In order that those skilled in the art to which this invention appertains may understand how to make and use the same, I will describe its construction in detail referring by numerals to the accompanying drawings 55 forming a part of this application, in which:—

Figure 1, is a perspective view of an expanding wallet having my improvement applied thereto.

Fig. 2, is a vertical section through the same.

Fig. 3, is a similar fragmentary view thereof on an enlarged and exaggerated scale.

Fig. 4, is a transverse or horizontal sectional view thereof on an enlarged and exaggerated scale showing a card in dotted lines to illustrate the manner in which it is inserted.

Fig. 5, is a cross section of the outer wall with a flap or closure formed therewith showing the runners attached thereto or prior to said outer wall and runner being applied to the wallet.

Fig. 6, is a perspective view of one of the runners showing the manner in which it is folded prior to being pasted together.

Fig. 7, is a similar view after the two parts of the runners have been folded together and the end bent over for application.

Fig. 8, is an enlarged cross section of one of the runners after being pasted.

Fig. 9, is a cross sectional view of an enlarged and exaggerated scale of a slightly modified form of my invention showing the flap or closure of the wall formed as a part of the inner wall.

Fig. 10, is a similar view of a still further modified form of my invention.

Fig. 11, is a cross sectional view of the outer wall with the runners formed integral therewith already being attached to the wallet.

Fig. 12, is a fragmentary front elevation of the outer wall showing the end of one of the runners.

Fig. 13, is an inside face view thereof.

Fig. 14, is a vertical sectional view of the outer wall looking toward one of the runners.

Fig. 15, is a fragmentary face view of the outer wall showing the manner in which it is cut and illustrating the cross lines where said wall is folded to produce the runner.

Fig. 16, is a similar view showing the first fold made.

10 Fig. 17, is also a similar view showing the second fold made and illustrating by a broken line the edges of the under parts.

Fig. 18, is a vertical sectional view of a wallet showing a different application of my 15 improvement.

Fig. 19, is a face view of a card holder having a transparent face held in place by runners made in accordance with my invention.

20 Fig. 20, is a section on the line 20—20 of Fig. 19.

Fig. 21, is a section on the line 21—21 of Fig. 19.

Fig. 22, is a fragmentary face view of the outer wall as it is cut ready to be folded 25 for producing a different form of my device.

Fig. 23, is a similar view showing the first fold made.

Fig. 24, is also a similar view after the 30 folding has been completed.

Fig. 25, is a transverse section of an outer wall illustrating the use of my single ply runners.

Fig. 26, is a perspective view of a slightly 35 modified form of runner showing the first step or fold in the formation thereof.

Fig. 27, is a similar view showing the ends bent over for application of the runner to a wallet or the like.

40 Fig. 28, is a fragmentary face view of the outer wall in the form of a blank in which the runners are an integral part thereof.

Fig. 29, is a similar view after the parts have been folded.

45 Fig. 30, is a transverse sectional view thereof.

Fig. 31, is a fragmentary face view of the outer wall as a blank showing a slightly modified form of construction.

50 Fig. 32, is a similar view with the parts folded, and

Fig. 33, is a transverse section thereof.

In carrying out my invention as here embodied I will describe the same in conjunction with an envelop or wallet 2 which may be of any well known form either in the shape of an ordinary envelop, a box envelop or with bellows giving it the necessary expansion and includes the side walls 3 and 4, 55 the side wall 3 being made of two thicknesses of material designated by the numerals 5 and 6, the latter being ordinarily termed the lining and between these walls are secured the edges of the bellows walls,

said edges being designated by the number 7. 65

The side wall 4 includes an inner wall 8 and an outer wall 9, the latter as here shown having an extension or flap 10 formed integral therewith which is adapted to fold over 70 and close the open end or mouth of the envelop.

In that form of my invention illustrated in Figs. 1 to 8 inclusive, the runners 11 are formed of separate strips and secured to 75 the outer wall 9 in spaced relation and in such positions that they will run parallel to each other preferably along or adjacent opposite edges of the completed envelop or wallet. 80

The runners 11 are produced by taking a strip of material and folding the same longitudinally so that the two parts or sections 12 and 13 are superimposed one upon the other with the part or section 13 of less 85 width than the part or section 12 so that the latter has a partly exposed inside face and these two sections or parts are preferably although not necessarily attached to each other as by a suitable adhesive so that when complete they become inseparable as shown in Fig. 8, thereby producing a double thickness folded edge 14. 90

Two or more of these runners are secured to the outer wall 9 in spaced relation with 95 the double thickness folded edges 14 of co-acting runners toward each other as plainly shown in Figs. 4 and 5 by pasting the single thickness of the part 12 to the outer face of the outer wall with the part 13 lying against 100 said outer face of the outer wall 9 so that those portions of said runners which are of double thickness are free from the outer wall 9 thereby producing a space into which the edges of a card 15 may be inserted, one 105 edge of said card being first inserted beneath one runner and the card then bowed outward to permit the insertion of the opposite edge of said card beneath the other runner so that when said card returns to its normal flat 110 shape, both edges will be held beneath the runners against accidental displacement.

The runners are of sufficient length so 115 that when secured to the outer face of the outer wall 9, the ends thereof project beyond the edges of said outer wall and these are then bent over to form the tabs 16 which are preferably reduced in width so as to leave a single thickness and said tabs may be pasted to the inner face of said outer wall 120 9 thereby forming top and bottom walls 17 for the space produced between the double walls of the runners and the outer face of the outer wall 9 and said top and bottom walls act as stops for the card to prevent 125 the same from becoming accidentally displaced or from shifting about on the wallet.

If found desirable the tabs may be dis-

pensed with and the ends of the runner secured or attached in any suitable manner to the outer face of the outer wall 9.

In actual practice the strips from which the runners are formed have one face covered with an adhesive so that when said strips are folded the two parts 12 and 13 will adhere to each other and will leave a portion of the inner face of the part 12 which is covered with the adhesive exposed so that the runners may be attached to the outer wall 9. Any desirable adhesive may be used, but a convenient one is what is known as a dry adhesive so that it may be applied to the strips and will become dry the same as that used on flaps of envelopes or postage stamps making it only necessary to dampen the adhesive when the parts are being made up.

20 The runners are attached to the outer wall 9 as shown in Fig. 5 and said outer wall with the runners is secured to the side wall 4 of the envelop or wallet by pasting said outer wall to the inner wall 8 and when 25 these two walls are secured together the edges 7 of the bellows walls are interposed between said walls 8 and 9.

Where the envelop or wallet is provided with a fastening tape 18 the same is passed 30 through a hole formed in the outer wall at the crease or score dividing the outer wall from the flap 10 and when that part of the tape lying across the outer wall 9 is secured between the latter and the inner wall 8 with 35 the ends of the tape free so that they may be passed part way around the wallet to keep the wallet from opening or the flap from swinging loose.

As will be plainly seen in Fig. 1 when a 40 card is placed upon the wallet and held in position by my improved card holder, said card will be exposed for the entire length thereof so that written or printed matter may be displayed from one edge to the other 45 throughout the entire length of the card and as these wallets are generally in a filing case in a vertical position other wallets may be placed in front of those already in the case without any part of the inserted wallet 50 or wallets catching on any part of the wallets in the case because of the smooth plain surface presented by the card and because the wallet is without obstructions or strips across the face of said card.

55 Further as the card does not have to be slipped into a pocket, the same cannot catch upon any part of the wallet which would be likely to tear the same nor can it force its way through the parts making up the card 60 holder so as to pull any part thereof loose from the other parts.

The modification shown in Fig. 9 is constructed in identically the same manner as above described, the only exception being

that the flap or closure 10 is formed as an 65 integral part of the inner wall 8 instead of being carried by the outer wall 9 and said outer wall is of the same dimensions as the envelop or wallet.

In the device illustrated in Figs. 10 to 17 70 inclusive the runners are formed as an integral part of the outer wall 9 and in such construction said wall 9 is provided at two opposite sides with extensions 19, one of which is shown in Figs. 15 to 17. The extension illustrated includes the material between the dotted line 20 and the adjacent parallel edge and said dotted line represents a crease or scored line where a fold is made, so that the material between two such lines 80 is the outer wall 9. The reduced ends of the extensions project beyond the two free or top and bottom edges of the outer wall 9 as in Fig. 15 so that when the parts are folded to produce the runners said projecting 85 ends form the tabs 16, Fig. 17.

Between each crease line 20 and the adjacent parallel edge of the sheet of material is formed another crease or scored line denoted by the dotted line 21, and the extensions are first folded inward along said crease lines 21 and preferably pasted to the same face of the sheet of material thereby providing the double thickness folded edge 90 14. Next the extensions are again folded inward along the crease line 20 and those portions of the extensions lying between the lines 20 and the folded edges 22 are pasted to the same face of the outer wall 9 as shown in Figs. 11 and 17 thereby forming the runners 11 with the two ply portions free from the outer wall 9 so as to leave spaces for a card between said two ply portions of the runners and the outer face of the outer wall 95 100.

When the runners have been formed as 105 shown in Fig. 17 the tabs 16 are projecting beyond opposite edges of the outer wall 9 and to complete the card holder the tabs of each runner are folded inward toward each other and if found desirable, may be pasted 110 to the inner face of the outer wall 9 as shown in Figs. 13 and 14.

After the runners have been completed the outer wall 9 with said runners is attached to the envelop or wallet by pasting 115 the same to the inner wall 8.

Fig. 18 illustrates the manner in which the runners may be attached to a completed wallet, wherein the tabs 16 of the runners 120 120 are folded over the edges of the outer wall 9 and fastened to the outer face of the gusset.

In place of a wallet or envelop a single sheet of material 26 Figs. 19 to 21, may be used with the runners thereon and a sheet 125 of transparent material 27 such as celluloid inserted for holding a card or other object between them.

In Figs. 22 to 24 I have illustrated a way of cutting and folding a sheet of material so that the ends of the runners may be attached to the outer face of the wall 9 whether or not the runners are made as an integral part of the outer wall as here shown. In this form of the device, the material between the dotted line 28 and the adjacent parallel edge is utilized as the runner 10 and this material is folded upon itself along the dotted line 29 forming a relatively narrow strip 30 which is of less width than the material between the two dotted lines 28 and 29 so that the exposed portion or the 15 part between the free edge of the strip 30 and the dotted line 28 of what becomes the inner face of the material between said dotted lines 28 and 29 may be attached to the face of the outer wall 9 and the ends of 20 the strip 30 are cut off a desirable distance so that said strips 30 are of less length than the material between the dotted lines 28 and 29 as well as the outer wall 9 thus leaving a further exposed portion of what becomes 25 the inner face of the material between said dotted lines 28 and 29 at the ends of the strip 30 whereby the ends of the runners may be attached to the outer wall 9 as will be obvious from Fig. 24.

30 Although from actual experience I have found it advisable to use runners so folded as to provide double walls throughout a portion of their width, yet this is not absolutely necessary and single ply runners 35 may be used with their inner edges free from the outer wall 9 to permit the insertion of a card, as shown in Fig. 25.

The runners illustrated in Figs. 26 and 27 are identical in construction with those 40 illustrated in Figs. 6 and 7 except that the part or section 13 is the same length as the reduced portion of the part of section 12, so that when the ends or tabs 16 are bent over to fasten the runners in place, the ends of 45 the part or section 13 will not be folded over as shown in Fig. 7, or in other words, the part or section 13 is of the same length as the wall to which the runners are attached, providing but a single ply on the 50 reverse side, thereby greatly reducing the thickness where the different parts are fastened together.

In Figs. 28, 29 and 30, I have illustrated one way in which the runners may be 55 formed as an integral part of the outer wall 9, which may, as above described, be provided with a flap 10, although in some cases it may be formed without such a flap.

At two opposite ends the outer wall is 60 provided with end flaps 35 adapted to be folded inward along the dotted lines 36 and the body of the outer wall is then slit along two parallel lines 37 between the two dotted lines 36 and further slit from the ends of

the first named slits outward at right angles to said first named slits along the dotted lines 36 as at 38. The material thus partly cut from the outer wall is folded inward upon the inner face of the outer wall along the dotted lines 39 thereby leaving slots 40 and forming the two ply runners 11. When this outer wall with its integral runners is pasted or secured to the inner wall 8, a complete side wall is formed and after being properly positioned, the end flaps 35 are 75 folded over the wall attached thereto.

The inner wall referred to may be the lining of a wallet or the like or it may be a sheet of suitable material of the proper size attached to the back of the outer wall and it is to be understood that when the backing element and the outer wall are fastened together the folded in parts or sections of the runners are free from said backing element, thereby permitting the ready insertion of a 85 card beneath said runners in the same manner as hereinbefore stated.

By forming the outer wall with the end flaps 35, the runners may be made the entire length of the device, but where this is not 90 essential, the flaps 35 may be dispensed with and the slits 37 terminated short of the ends of the outer wall, as shown in Figs. 31, 32 and 33, but otherwise the construction, formation and operation is identical with that 95 form illustrated in Figs. 28 and 29.

It is to be understood that where I describe the parts as pasted this is also to include stitching, stapling or other suitable modes of attaching.

Of course I do not wish to be limited to the exact details of construction as herein shown as these may be varied within the limits of the appended claims without departing from the spirit of my invention.

Having thus fully described my invention, what I claim as new and patentable is:—

1. In a device of the character stated the combination with a wallet including an outer wall, of a pair of spaced parallel runners secured to the outer face of said wall and having their ends folded over and secured to the inner face of said wall, the inner edges of said runners being free to permit the insertion of a card.

2. The combination with a wallet including an outer wall, of a pair of parallel spaced runners carried by said wall and disposed across the outer face thereof with the ends of said runners folded over and secured to the inner face of said wall, said runners each comprising a strip folded upon itself to form a single thickness throughout a portion of its width, a two ply thickness throughout the other portion of its width, the said single thickness being fixed to the outer face of the said outer wall

and the two ply portion being free to permit the insertion of a card and forming a two ply folded inner edge.

3. A card holder for wallets including an outer wall of said wallet, runners each comprising a strip of material folded upon itself longitudinally to provide a single thickness throughout a portion of its width and a two ply thickness throughout the other portion of its width, said runners being carried by the outer face of said outer wall spaced apart and having the two ply portions free with the folded edges facing each other.

15 4. A card holder for wallets comprising an outer wall of a wallet, extensions formed therewith at two opposite sides, said extensions being longer than the main outer wall, each of said extensions being folded inward longitudinally on itself and pasted to form a two ply portion and a single ply portion, said extensions being further folded inward along lines spaced from the turned in edges of said extensions with the single ply portions secured to the outer face of the outer wall leaving the two ply portions free thereby forming runners beneath which may be inserted the edges of a card, the projecting ends of said runners being folded over and secured to the inner face of said outer wall.

30 5. A card holder comprising a sheet or wall, extensions formed therewith at two opposite sides, said extensions being longer than the main outer wall, each of said extensions being folded inward longitudinally on itself to form a two ply portion and a single ply portion, said extensions being further folded inward along lines spaced from the turned in edges of said ex-

tensions with the single ply portions secured to the outer face of the outer wall leaving the two ply portions free thereby forming runners beneath which may be inserted the edges of a card, the projecting ends of said runners being folded over so as to contact with the inner face of said outer wall.

6. In a device of the character stated, the combination with a wallet, of a pair of spaced parallel runners disposed across the outer face of one of the wallet walls with the ends of said runners folded over and attached to another of said wallet walls, said runners each comprising a strip folded upon itself to form a two ply thickness throughout a portion of its width and leave a single ply thickness throughout the remainder of its width.

7. A runner for card holders comprising a strip of material folded upon itself longitudinally, one of the folded over sections being of greater width and length than the other, the projecting ends forming attaching tabs.

8. In a device of the character stated, the combination with a wallet, of a pair of spaced parallel runners on the outer face of one of the walls thereof and having their ends folded over and secured to the inner face of said wall, the inner edges of said runners being free to permit the insertion of a card.

9. An envelop or wallet having spaced parallel runners, each having a portion folded upon itself to produce a rounded edge for the easy insertion of a card.

In testimony whereof I have hereunto affixed my signature.

ALVAH BUSHNELL, JR.
